DESIGN FOR AN EMBROIDERED TRIMMING OR THE LIKE

Beatrice Friedman, New York, N. Y.

Application January 3, 1947, Serial No. 135,921

Term of patent 7 years

(Cl. D92—1)

To all whom it may concern:

Be it known that I, Beatrice Friedman, a citizen of the United States, residing in New York city, in the county of New York and State of New York, have invented a new, original, and ornamental Design for an Embroidered Trimming or the like, of which the following is a specification, reference being had to the accompanying drawing, forming part thereof.

The figure of the drawing is a plan view of a piece of an embroidered trimming or the like showing my new design.

I claim:

The ornamental design for an embroidered trimming or the like, substantially as shown.

BEATRICE FRIEDMAN.
